UNITED STATES PATENT OFFICE.

WILLIAM A. JAMESON, OF NIAGARA FALLS, NEW YORK.

DESIGN FOR A HANDLE OF SPOONS, FORKS, OR SIMILAR ARTICLES.

No. 37,955.

Specification for Design.

Patented April 17, 1906.

Application filed March 15, 1906. Serial No. 306,304. Term of patent 7 years.

To all whom it may concern:

Be it known that I, WILLIAM A. JAMESON, a citizen of the United States, residing at Niagara Falls, in the county of Niagara and State of New York, have invented a new, original, and ornamental Design for Handles of Spoons, Forks, or Similar Articles, of which the following is a specification, reference being had to the accompanying drawings, forming a part thereof.

Figure 1 is a front plan view showing my design. Fig. 2 is a rear plan view showing my design.

I claim—

The ornamental design for the handle of a spoon, fork or similar article as shown.

WILLIAM A. JAMESON.
